UNITED STATES PATENT OFFICE.

MARY S. HOOD, OF NEWARK, NEW JERSEY, ASSIGNOR TO CHENEY BROTHERS, OF SOUTH MANCHESTER, CONNECTICUT, A CORPORATION OF CONNECTICUT.

DESIGN FOR A TEXTILE FABRIC.

No. 38,117.

Specification for Design.

Patented July 3, 1906.

Application filed May 31, 1906. Serial No. 319,655. Term of patent 3½ years.

To all whom it may concern:

Be it known that I, MARY S. HOOD, a citizen of the United States, residing at the city of Newark, in the county of Essex, State of New Jersey, have invented a new, original, and ornamental Design for Textile Fabrics, of which the following is a specification, reference being had to the accompanying drawing, forming a part thereof.

The figure is a plan view of the fabric, showing my new design.

I claim—

The ornamental design for a textile fabric, as shown.

MARY S. HOOD.
